Primary Examiner — L. A. Grabenstetter(74) *Attorney, Agent, or Firm* — Justin Lampel**CLAIM**

The ornamental design for a mobile phone holder, as shown and described.

DESCRIPTION

FIG. 1 is a perspective view of a mobile phone holder showing my new design;

FIG. 2 is a front side view thereof;

FIG. 3 is a rear side view thereof;

FIG. 4 is a right side view thereof;

FIG. 5 is a left side view thereof;

FIG. 6 is a bottom plan view thereof; and,

FIG. 7 is a top plan view thereof.

The broken lines depict portions of the mobile phone holder that form no part of the claimed design.
